EMBOSSED PAPER NAPKIN OR THE LIKE

William F. Erisman, Greenfield, Mass., assignor to Erving Paper Mills, a corporation of Massachusetts

Application April 13, 1951, Serial No. 14,828

Term of patent 14 years

(Cl. D59—2)

To all whom it may concern:

Be it known that I, William F. Erisman, a citizen of the United States, residing at Greenfield, county of Franklin, and State of Massachusetts, have invented a new, original, and ornamental Design for an Embossed Paper Napkin or the like of which the following is a specification, reference being had to the accompanying drawing, forming part thereof.

The figure is a face view of one quarter of an embossed paper napkin, the whole napkin showing my new design. The other three quarters of the napkin are arranged in proper relationship to complete napkin.

I claim:

The ornamental design for an embossed paper napkin or the like, as shown and described.

WILLIAM F. ERISMAN.
